UNITED STATES. PATENT OFFICE.

JOHN W. D. McDONALD, OF BEMBRIDGE, ISLE OF WIGHT, GREAT BRITAIN.

FOLDING BOAT.

SPECIFICATION forming part of Letters Patent No. 224,346, dated February 10, 1880.

Application filed May 10, 1879. Patented in England, July 30, 1878.

To all whom it may concern:

Be it known that I, JOHN WALLACE DOUGLAS McDONALD, of Bembridge, in the Isle of Wight, Kingdom of Great Britain and Ireland, rear-admiral in the royal navy, have invented new and useful Improvements in Folding Boats, of which the following is a specification.

My improved folding boats or vessels are composed of longitudinal sections or parts, (tapered or gradually narrowed toward each end,) of stiff bendable elastic material, connected together by continuous longitudinal water-proof hinges or joints.

Such a boat or vessel may be constructed so that when closed up it will be flat, and when opened out the curvature of the bottom of the boat, as seen in side elevation, will conform (or approximately so) to the curvature of the lower edge of the longitudinal section or part constituting the juxtaposed side, as seen in side elevation, when the vessel is open, and the curvature of each side of the boat or vessel, as seen in plan, will correspond (or approximately so) to the curvature of the outer edge of the juxtaposed longitudinal section forming part of the bottom of the boat or vessel, as seen in plan, when the vessel is open.

The boat or vessel may be kept expanded or opened out for use by thwarts and stretchers.

The material employed in the construction of the longitudinal parts or sections is wood, steel, or other substance such as will automatically resume its normal flat or plane form when the thwart or stretcher is withdrawn.

Referring to the accompanying drawings, Figure 1 shows, in side elevation, a vessel constructed according to my invention, the vessel being in this view shown open. Fig. 2 is a plan view of the same vessel, also showing it open, but with the masts lying down. Fig. 3 is a plan view of the vessel, showing it closed up or folded. Fig. 4 is a cross-sectional view, showing the vessel closed up or folded.

In this vessel the bottom 1 is made in one piece. It may be of pine, or mahogany, or other suitable wood. The shape of the bottom is seen in Fig. 3 by the outer line, 2, which indicates the configuration of the bottom. To each side of the bottom is hinged or jointed,

by a continuous hinge or joint of leather, 3, a side, 4, which may be of similar material to the bottom of the boat or vessel, or of other analogous or suitable material. The lower edge of each of these sides is originally made of precisely the same configuration as the corresponding or juxtaposed side of the bottom 1, so that, when a side and bottom are both flat, if one be laid upon the other the curved edges of the same, respectively, shall coincide, or nearly coincide.

The mode in which I have found it convenient in practice to form the hinges or joints is shown clearly in Fig. 4, where 3 3 are strips of leather prepared in oil in the same way as leather is prepared for making fire-hose, (leather pipes.) In England this leather is called "hose-butts."

5 and 6 are battens or strips of substance able to bend to the curve of the bottom of the boat or vessel without breaking, and sufficiently hard and tough to hold a clinched copper nail or a rivet. American elm is very suitable for this purpose. If soaked in water for about twenty-four hours it may be readily bent to the required curvature.

The strips of leather are secured to the curved sides of the bottom 1 by copper rivets or nails passed through the battens 5, through the leather, and through the bottom 1, and carefully clinched or burred. The sides 4 are similarly fastened to the strips of leather. The sides are shorter than the bottom of the boat or vessel. At the ends chocks 7 and 8 are secured to the bottom 1.

It will be evident that a boat or vessel constructed as just described may be opened out, as shown in Figs. 1 and 2, and may be kept so opened out by a variety of devices or contrivances. In the boat or vessel illustrated, pieces of wood or metal 9, which I call "spreaders," are secured by hinges 10 to the inside of the bottom of the boat. These spreaders are provided with mast clasps or clamps 11, in which the lower ends of the masts fit and are held. The form of these spreaders, as shown in Fig. 2, is such that, supposing the boat or vessel to be closed or folded up, as shown in Fig. 3, if the masts be now pulled up they will, in conjunction with the spreaders, operate as

levers for partially opening the boat or vessel, the sides of which will, as the masts are raised, be gradually moved apart by the curved portions 9^x of the spreaders.

5 The vessel may be kept open by thwarts or cross-seats 12. A convenient mode of guiding and supporting these thwarts or cross-seats is by risings or ledges 13, fastened to the sides of the vessel and having tapered pieces of 10 wood or guides 14 above them. In the ends of the thwarts or cross-seats recesses are formed, corresponding in length to the width at the base of the tapered guides 14, so that as the ends of the thwarts or seats are pressed down 15 they are guided into their proper places.

15 and 16 are stays or ropes for keeping the masts up, as shown in Fig. 1.

In some cases I construct boats or vessels in longitudinal sections or parts, connected together by continuous longitudinal water-proof 20 hinges on my plan, to close up into a hollow form somewhat resembling that of the well-known cigar-ship. Such boats, of different sizes, may be stowed one within another, so as 25 to economize space.

It is to be understood that in all cases the juxtaposed edges of stiff bendable elastic material must be of precisely similar form—that is to say, for a straight joint the two edges must 30 be straight; for a curved joint the two edges must have precisely the same curve as I have above explained with reference to the examples illustrated.

In making the curved edges of the bottoms 35 and sides of vessels such as those I have illustrated, the curve should correspond to the natural curvature of a strip of wood when bent by moving its two extremities toward each other.

40 In practice, I find that I can obtain a suitable and proper curve, which gives good results, as follows: I draw a straight line, corresponding to the longitudinal center of the vessel. Across this line and at right angles 45 thereto I draw three other lines, at equal distances apart. The two outer of these cross-lines correspond to the extremities of the intended vessel. On each of these two outer lines I make a mark at a distance above the 50 longitudinal line equal to one-half of the width at the narrowest part of the intended vessel. On the central cross-line, above the longitudinal line, I place a mark at a distance above the longitudinal line equal to half the 55 greatest width of the bottom of the intended vessel. I then lay a straight strip of wood on the surface so marked, and by moving the two ends of this piece of wood toward each other I bend the wood so that it shall touch the 60 three points above indicated, and shall produce a fair curve, like that given by a penning batten. The bend of the wood then correctly indicates a suitable curve.

Sometimes I cover the wood or stiff bendable elastic material (except metal) with can-

vas fastened on by means of marine glue. Such a covering may be used on one side only of the wood, or on both sides thereof.

Sometimes I make the stiff bendable elastic portions of my boats of two thicknesses or 70 layers of wood secured together by marine glue, with the grain of the one thickness or layer of wood at right angles to or crosswise of the other thickness or layer of wood, and there may be a layer of canvas interposed between the two thicknesses or layers of wood, or not. 75

It is to be understood that I do not confine myself to the use of wood in forming the stiff bendable elastic portions forming the sides 80 and bottoms of my boats or vessels.

What I claim is—

1. The combination, in a folding boat or vessel, of longitudinal sections or parts of stiff bendable elastic material having the juxtaposed edges of similar shape or curvature, and continuous water-proof hinges or joints connecting the said longitudinal sections or parts together, substantially as and for the purpose hereinbefore described. 90

2. The combination, in a folding boat or vessel, of a bottom, 1, of wood or other stiff bendable elastic material curved at both its longitudinal edges, two sides, 4, of similar material and having their lower edges similarly 95 curved, and two continuous hinges or joints of leather, 3, connecting said sides to said bottom, substantially as described.

3. The combination, in a folding boat or vessel, of a bottom, 1, of wood or other stiff bendable elastic material curved at both its longitudinal edges, two sides, 4, of similar material and having their lower edges similarly curved, two continuous hinges or joints of leather, 3, connecting said sides to said bottom, risings 100 or ledges 13, fastened to said sides, tapered pieces or guides 14, fixed above said risings or ledges, and thwarts or cross-seats with recessed ends, all substantially as and for the purposes specified. 110

4. The combination, in a folding boat or vessel, of a bottom, 1, of wood or other stiff bendable elastic material curved at both its longitudinal edges, two sides, 4, of similar material and having their lower edges similarly curved, two continuous hinges or joints of leather, 3, connecting said sides to said bottom, means for keeping said boat or vessel open, and spreaders or openers 9, secured by hinges to the bottom of the boat, all substantially as and for the purposes specified. 115 120
